5 Claims. (Cl. 179—171)

A requirement frequently arising in radio intelligence transmission is to transmit not only a definite radio frequency but it is occasionally demanded that within a certain range or band a change of wave length should be possible without the incidental necessity of retuning the various stages of the sending or receiving signal amplifier.

It is known in the art of these amplifiers to differently tune the oscillatory circuits of the various stages in respect to one another and to introduce, where necessary, additional damping. The band width thus obtainable is comparatively limited if the efficiency of the gain is to stay high.

It is also known in the prior art to intercouple the sequential stages of a radio frequency amplifier by networks or filters, the latter having a band-pass commensurate to the wave band within which the transmission efficiency is to be uniform. This circuit organization has the drawback that it is very difficult to obtain a uniform efficiency over the desired tuning range, especially where transmitter amplifiers are operated as class C amplifiers. Over any considerable band width, undesirable harmonics are also transmitted.

The invention obviates these difficulties. The invention is predicated upon the consideration hereinafter to be outlined and which may be taken into consideration, for instance, in connection with the load of the power stage of a transmitter amplifier in conjunction with a tuned damped antenna.

The power stage, when it is resonant, has as its only load the ohmic resistance of the antenna. In other words, a pure ohmic or active load is involved, while in the absence of resonance capacitive or inductive reactance powers are involved, and these must be introduced in the oscillation circuit from the outside in order that a constant potential may be maintained in the circuit.

Now, if care is taken so that when a wattless current is wanted in a certain part of the circuit, corresponding wattless currents of opposite sign are derived from a tube, it must be possible, at least inside a restricted transmission range, say, inside an octave to provide an ohmic load for all frequencies of the range or band, and this implies or presupposes uniform amplification of the particular band under consideration.

The invention is concerned thus with a radio frequency amplifier circuit organization for the transmission of a definite frequency of a wave band, say, an octave, the outstanding feature of which is that the wattless currents arising when

the frequency deviates from the resonance frequency of the tuned load are compensated by wattless currents of opposite sign supplied from a tube.

5 A more detailed description follows, wherein Figure 1 shows a preferred circuit arrangement embodying the invention;

Fig. 2 is a graphic representation of a certain frequency response characteristic;

Fig. 3 shows graphically a coordination between the wattless power and the plate dissipation observed in the operation of a certain discharge tube of my system; and

Fig. 4 shows a modified circuit arrangement for carrying out the invention.

Referring to Fig. 1, the potential E arising across the input terminals 1 and 2 is impressed through voltage divider 3 and lead 4 upon the control grid 5 of pentode 6. Included in the output circuit of the tube 6 is the load 7 represented in the form of an oscillatory circuit comprising a paralleled ohmic resistance, said load being, for instance, an antenna of around 25 to 30 percent damping. If the plate alternating potential is practically constant in the presence of variations of frequency, then the current which flows through this circuit has a shape as shown graphically in Fig. 2 where the plate alternating current I_a is plotted as a function of the frequency f .

20 In the presence of resonance frequency f_r , current I_a has a good power factor. But upon departure from the resonance frequency either upwards or downwards, the plate a. c. will be increased as a result of the production of capacitive or inductive wattless currents.

25 However, it will be understood that the plate alternating potential can be stabilized only if the wattless current arising upon the departure from the resonance frequency is supplied from the outside. For in this manner conditions can be made so that not only for the resonance frequency, but rather for a comparatively broad band, there is, as it were, permanently a purely resistive load, with the consequence that the power factor remains constant even in the presence of frequency variations. This condition as shown, for example, in Fig. 1 is attainable by connecting in parallel relation to the main amplifier channel 8, 9 a tube 10 which is so controlled that it will furnish the 30 wattless current required for compensation. Tube 10 receives its control potential by way of a condenser 11 and a resistance 12 causing the requisite phase shift, from one and the same voltage divider 3, the latter supplying also the potential for the tube 6. In parallel relation to the grid-

cathode path is arranged a voltage resonance circuit 13 which comprises the capacity 14 and the inductance 15 as well as the grid leak choke-coil 16. The input and circuit capacities of the grid circuit are indicated by the dash-line condenser 17.

Resonance circuit 13 is tuned to the same frequency as circuit 7 in the output circuit. In the presence of a resonant condition circuit 13 constitutes a short-circuit path for the control frequency so that tube 10 receives practically no appreciable control potential. Upon departure from the resonance frequency, the tube furnishes a wattless component designed to compensate the wattless component of circuit 7. The compensatory action and thus the band-width are restricted by virtue of the fact that below the resonance frequency current resonance is conditioned by capacitor 14 and inductance 16, while above the resonance frequency the choke-coil 15 and the capacitor 17 form a further current resonance point beyond which—always figured and viewed from the resonance point of circuit 13—the control potential thus far rising is caused again to decline speedily.

In order to make sure that the wattless current furnished from tube 10 will be always proportional to the potential drop in circuit 13, it is imperative that tube 10 should operate within a certain limited range of class A, class B, and class C amplification, because of the variability of the grid potential. Tube 6, as will be understood, should work as a class C amplifier for the sake of improved efficiency, as is customary in amplifiers forming a part of transmitters.

Now, it has been ascertained that the provision of a tube designed to supply additionally the wattless current is not always necessary. On the contrary, the main amplifier may be relied upon to furnish the wattless power. This discovery was made only after exhaustive research and calculations the findings of which will be further explained. The conditions such as they are, may be described by reference to a pentode, which is particularly suited to the circuit under discussion, because the reaction of the plate upon the grid is practically absent, due to the limited value of the grid plate capacitance and the small influence of the plate voltage upon the plate current.

Fig. 3 shows what active and reactive or wattless powers may be secured from a pentode for different plate D. C. voltages. The assumption is here made that the plate dissipation of the tube is stabilized; to be more precise, that it is equal to the maximum admissible value. Another presupposition is that the plate alternating potential is driven always close to the limit between under-volted and over-volted operation. Of course, to the various points of the curve correspond load impedances the size and phase of which are given by the straight line from the origin to the points of the curve. Plotted on the abscissae is the "active yield," in other words, the ratio of active power to plate dissipation, and on the ordinates the "reactive yield"; that is to say, the ratio of wattless power to plate dissipation, the parameters being the plate D. C. voltage, though the values indicated alongside the graphs are merely relative figures or proportional numbers. The further assumption is made that the current flow angle is constant and that it amounts to 60 degrees. This angle, by definition, indicates what angular proportion of the entire control potential is co-

ordinated to the range in which plate current flows. In order to simplify the calculations it is customary to designate one-half of this angular proportion as the current flow angle. For instance, in the case of class A amplifier operation, the said angle amounts to 180 degrees; for pure class B operation, it is 90 degrees, and for C operation correspondingly less.

With due regard for the efficiency in the case of resonance, the tube works also under conditions of class C operation. In the case of the circuit organization shown in Fig. 1 where the tube 10 furnishing the wattless current could not be operated satisfactorily as a class C amplifier, particularly due to the variable grid voltages. Hence it was at first thought that difficulties would be encountered in obtaining the simultaneous delivery of active and wattless current as output from a single tube, especially when operated as a class C amplifier. However, it has been discovered that such operation is entirely feasible.

In the first place this surprising fact is found that for $\cos \phi = 0$ the wattless power is practically independent of the plate D. C. voltage, and that, moreover, it is appreciably lower than the maximum watt or active power. But if from one and the same tube watt and wattless power be taken simultaneously, it is found that the wattless component of the tube becomes considerably higher than in the case of purely wattless operation. For instance, for parameter 14 the wattless yield in the presence of $\phi = 90$ degrees is only .91; for $\phi = 39$ degrees, it is =1.6, while the active power yield becomes equal to 2. In other words, maximum wattless yield is secured in a tube, if at the same time a watt component of roughly the same value is taken off.

The graphs Fig. 3 show that a comparatively large watt and wattless component is simultaneously derivable from the tube without the plate dissipation of the tube being made excessive. However, these findings suggest that the elimination of the additional or separate tube to furnish the wattless component shown in the circuit scheme Fig. 1, and furthermore the main tube may be depended upon for the supply of the wattless component as shown, for instance, in Fig. 4. This main tube 20 (Fig. 4) corresponds with tube 6 in Fig. 1. It feeds to a load or consumer, say a more or less damped aerial. The damping can be produced by a parallel oscillation circuit 21 with paralleled resistance 28. Tube 20 receives its control potential from an input tube 22 which practically works with a constant input potential.

The grid circuit of tube 20, similarly as in the case of tube 10, Fig. 1, contains a voltage resonance circuit 23 in series with a resistance 26 in parallel relation to the grid-filament path or circuit which is tuned to the same frequency as the oscillatory circuit 21 in the output circuit of tube 20. The grid leak choke-coil is indicated at 24, while the input and circuit capacities represented by dash-lines are indicated at 25. In the presence of a state of resonance the control grid 27 of tube 20 is only impressed with the potential arising across the resistance 26.

In the case of departures from the resonance point the wattless potential occurring in the potential resonance circuit has the result that the tube will furnish wattless current in addition to the active or watt current, and this wattless or idle current will supply and cover the wattless current requirements of the consumer or load to a point such that the same will function like a

purely resistive load. The resonance circuits must be so proportioned that a relatively broad band is transmitted at uniform efficiency, say, a range of one octave.

The circuit organizations shown, by way of example, in the appended drawing comprise pentodes, though it will be evident that it is also possible to use triodes, if care be taken that the reaction caused by the plate upon the grid is practically compensated, say, by means of neutralizing circuits. 10

I claim:

1. A radio frequency amplifier circuit adapted to transmit a definite frequency of a frequency band covering at least an octave, said circuit having a discharge tube in combination with means including an auxiliary discharge tube whereby the wattless currents arising in the case of departure of the frequency from the resonance frequency of a tuned load device are compensated by wattless currents of opposite sign furnished by said tube. 15

2. A circuit according to claim 1, wherein the grid circuit of the auxiliary tube contains the seriation of an ohmic resistance and a voltage resonance circuit tuned to the same frequency as the load device, the same being so proportioned that the wattless currents required for compensation are furnished by the tube. 20

3. In a radio frequency amplifier, an electron discharge tube having input and output circuits, a load in said output circuit, said load being receptive to a band of frequencies covering at least one octave and being resonant at a frequency within said band, the inductive and capacitive values of said load being adjusted to develop predetermined values of wattless current components 25

5 at different frequencies within said band, and means including an auxiliary discharge tube for providing compensation with respect to said wattless current components such that a substantially uniform power factor is obtained throughout said band.

4. The combination according to claim 3 and including in parallel with said discharge tube a second discharge tube having an input circuit at least a portion of which is common to the aforementioned input circuit, and resonant means for feeding the control potential to the first said discharge tube, said resonant means being connected to an intermediate point on a voltage divider across the leads from a source of control potentials, and said second discharge tube being controlled by a relatively larger value of said control potentials. 15

20 5. An amplifier circuit arrangement in combination with a load having a substantially pure conductance at a predetermined frequency also having a capacitive susceptance above said frequency and an inductive susceptance below said frequency, means for automatically neutralizing the susceptance components comprising a variable impedance in shunt with said load, said means comprising a discharge tube the space path of which is in shunt relation to said load and the input circuit of which is energized from an input voltage common to that of said amplifier, but differing in phase therefrom, and means including a series resonant circuit in shunt with a portion of said input circuit for disabling said tube when said predetermined frequency is delivered by said amplifier to said load. 25
